BINDER ATTACHMENT FOR SEWING MACHINES

James E. Ackerman, Devon, Conn., assignor to
The Singer Manufacturing Company, Elizabeth, N. J., a corporation of New Jersey

Application July 23, 1945, Serial No. 606,637

7 Claims. (Cl. 112—138)

1

This invention relates to binders for use with sewing machines and more particularly to binders of the strip-inverting type.

The invention has for its object to provide an improved strip-inverting and edge-inturning binder that will permit ready insertion therein of the binding-strip and which will permit drawing therethrough of the strip with a minimum of applied force.

The invention both in structure and in operation, as well as to additional objects thereof, will be best understood from the following description taken in conjunction with the accompanying drawings in which:

Fig. 1 is a perspective view of the improved binder loaded with a binding-strip.

Fig. 2 is a top plan view of the binder.

Fig. 3 is a front side elevation of the binder.

Fig. 4 is an end elevation of the strip-receiving end of the binder.

Fig. 5 is a front end elevation of the strip-egress end of the binder.

Fig. 6 is a rear side elevation of the binder.

Fig. 7 is a sectional view taken substantially along line 7—7 of Fig. 3.

Fig. 8 is a sectional view taken substantially along line 8—8 of Fig. 3.

As shown in the accompanying drawings, the improved binder has an L-shaped supporting plate 1 provided with a slot 2 elongated lengthwise of the binder. The supporting plate 1 has an upturned portion 3 to which the inner or core-member 4 of the binder is secured by screws 5.

The core-member 4 comprises a block formed to provide an outer guide-wall of substantially horizontal U-shape. The upper horizontal face 6 of the core-member guide-wall is disposed slightly below the upper edge of and extends to the vertical wall portion 7 of the core rib 8, whereby the wall portion 7 may serve as a guide for the upper margin of a binding strip B. The wall portion 7 deflects the upper marginal portion of the strip vertically upwardly. As illustrated more particularly in Fig. 7 of the drawings, the lower core-member face 9, which is disposed substantially parallel to the upper face 6, terminates in a vertical shoulder 10 formed by a rib 11 depending from the core-member 4 adjacent the supporting-plate member 3. The rib 11 preferably extends throughout the length of the core-member and the shoulder 10 of the rib 11 provides an edge-guide for the lower edge of the binding-strip B.

Spaced from the core-member 4 to form therewith a horizontal U-shaped channel for the binding-strip B is a correspondingly shaped outer or

2

shell-member 12. The lower limb 13 of the shell-member 12 is disposed in binding-strip confining relation with the rib 11 of the core-member; said lower limb 13 extending under said rib 11 and being bent upwardly to be suitably attached to the back side of the core-member 4, as by screws 14. The forward receiving end portion of the shell-member 12 is flared outwardly as at 15 thereby to facilitate the insertion of the binding-strip between the core 4 and the shell-member 12. The forward portion of the upper limb of the shell-member is partly cut away at an inclination to the length of the binder and terminates approximately midway of the binder-length in a strip-margin engaging ear bent to provide a vertically disposed wall portion 16 and a horizontally disposed wall portion 17, which latter is secured by a screw 18 to the top surface of the rib 8. This ear cooperates with the core wall portion 7 in confining and in guiding the vertically upwardly directed margin of the strip B. The upper limb of the shell-member continues beyond the ear 16 to form a fold-defining shell-edge portion 19 which is spaced from and disposed in parallel relation with the rib 8. The shell-member 12 terminates substantially at the edge-guide 20 of the core-member 4 which is cut away and recessed to form the conventionally inclined and spaced strip-inverting edges 21 and 22, and to provide a body material edge-guide 20 between said edges.

Secured by screws 23 upon the upper face of the rib 8, at the strip-delivery side of the ear 8, is a fold-forming plate 24. The plate 24 overhangs the shell-edge 19 and is provided with a strip-folding edge 25 which is inclined away from the rib 8 in a direction toward the delivery end of the binder. As may be best seen from Figs. 3, 5 and 6, the free edge portion of the plate 24 is bent downwardly into contact with the shell 12 to form a depending strip-confining guide wall 26 which functions as a guide for the folded margin of the strip. The depending wall 26 is bent to curve about and to completely house the upper strip-delivery portion of the binder; said wall 26 being spaced from the strip-inverting edge 21 sufficiently to maintain the binding strip in snug engagement with the strip-inverting edge 21.

Secured by screws 27 to the back side of the core 4 is an angle member 28 whose edge portion 29 functions as a guide for the folded and inverted strip B.

The shell-member 12 is preferably provided along the bend thereof with the usual slot 30 to facilitate insertion of the binding-strip into the binder.

In introducing the binding-strip B into the

binder, the forward end portion of the strip is merely inserted between the shell edge 15 and the core 4; the edge of the upper margin being deflected upwardly by the wall 7 and being guided by the wall 17, while the edge of the lower margin is guided by the shoulder 10 of the core-member rib 11. As the binding-strip is passed through the binder, the upper margin of the strip is held in a vertical position by the wall 16 until the strip is deflected outwardly and away from the plane of the rib-wall 7 by the strip-folding edge 25 which thereafter folds the marginal portion downwardly upon the upper face of the shell-member 12. It has been found to be advantageous to construct the U-shaped strip-passageway with an angularly disposed or vertical limb defined by the rib-wall 7 and the shell-wall 16 (Fig. 8), for the reason that the marginal portion of the binding strip B guided by this limb is folded back through 90 degrees only as it passes from the receiving end of the attachment to the strip-inverting edge 21 thereof. The folding back of the binding strip through only 90 degrees, instead of through 180 degrees as in previous attachments of this type, reduces to a minimum the applied force necessary to draw the binding strip through the attachment. Also, the marginal portion of the binding strip which traverses the vertical portion of the strip-passageway is not subjected to as much stretch when it is bent through 90 degrees as it is when it is bent through 180 degrees, with the result that the binding strip is delivered to the stitching mechanism in a substantially unstretched condition. The finished seam consequently lies flat and is devoid of waviness.

The binding-strip is then inverted about the core-member edges 21 and 22 in the conventional manner, thereby inturning the folded margin of the strip; the depending wall 26 of the plate 24, together with the edge portion 29 of the angle-plate 28 suitably confining and guiding the strip. The wall 26 further functions as a guard for pile or other loose threads upon the upper face of a body material to which the binding-strip is to be attached.

Having thus set forth the nature of the invention, what I claim herein is:

1. A strip-reversing binder for sewing machines, comprising, a core-member widthwise formed to provide a U-shaped outer guide-wall having substantially parallel outer side faces and lengthwise terminating in an inclined strip-inverting edge, a rib projecting substantially at right angles from one of said side faces and extending longitudinally of said core-member, an outer shell-member formed and disposed with respect to said core-member to provide therebetween a U-shaped strip-folding channel, said shell-member having a fold-defining side edge thereof disposed adjacent the juncture of said rib and said core-member side face at the fold-inverting end of the core-member, a strip-margin folding plate carried by said rib and overhanging said fold-defining edge of the shell-member, and a strip-margin engaging member carried by said shell between said plate and the strip-receiving end of said binder, said strip-margin engaging member being formed and disposed with respect to said rib to provide therebetween a straight strip-guiding channel disposed at an angle to the upper limb of and communicating with said U-shaped channel.

2. A strip-reversing binder for sewing machines, comprising, a core-member widthwise

formed to provide a U-shaped outer guide-wall having substantially parallel outer side faces and lengthwise terminating in an inclined strip-inverting edge, a rib projecting substantially at right angles from one of said side faces and extending longitudinally of said core-member, an outer shell-member formed and disposed with respect to said core-member to provide therebetween a U-shaped strip-folding channel, said shell-member having a fold-defining side edge thereof disposed adjacent the juncture of said rib and said core-member side face at the fold-inverting end of the core-member, a strip-margin engaging member carried by said shell at a point remote from the fold-inverting end of the core-member, said strip-margin engaging member being formed and disposed with respect to said rib to provide therebetween a straight strip-guiding channel disposed at an angle to and communicating with said U-shaped channel, and a strip-margin folding plate carried by said rib and overhanging said fold-defining edge of the shell-member between said strip-margin engaging member and said inclined strip-inverting edge of the core-member, said plate having a free edge thereof inclined away from said rib at the point of termination of said strip-margin engaging member and toward the delivery end of the binder to overhang said shell-member.

3. A strip-reversing binder for sewing machines, comprising, a core-member widthwise formed to provide a U-shaped outer guide-wall having substantially parallel outer side faces and lengthwise terminating in a notched strip-delivery mouth providing spaced strip-inverting edges inclined to the longitudinal axis of the core-member, a rib projecting substantially at right angles from one of said side faces and extending longitudinally of said core-member, an outer shell-member formed and disposed with respect to said core-member to provide therebetween a U-shaped strip-folding channel, said shell-member having a fold-defining side edge thereof disposed adjacent the juncture of said rib and said core-member side face at the fold-inverting end of the core-member, a strip-margin folding plate carried by and disposed substantially at right angles to said rib and overhanging said fold-defining edge of the shell-member, and a strip-confining guide-wall depending from said strip-margin folding plate in spaced relation with one of said strip-inverting edges to provide therebetween a guide channel for the underfolded margin of the binding strip.

5. A strip-reversing binder for sewing machines, comprising, a core-member widthwise formed to provide a U-shaped outer guide-wall having substantially parallel outer side faces and lengthwise terminating in a notched strip-delivery mouth providing spaced strip-inverting edges inclined to the longitudinal axis of the core-member, a rib projecting substantially at right angles from one of said side faces and extending longitudinally of said core-member, an outer shell-member formed and disposed with respect to said core-member to provide therebetween a U-shaped strip-folding channel, said shell-member having a fold-defining side edge thereof disposed adjacent the juncture of said rib and said core-member side face at the fold-inverting end of the core-member, a strip-margin folding plate carried by and disposed substantially at right angles to said rib and overhanging said fold-defining edge of the shell-member, a strip-confining guide-wall depending from said

strip-margin folding plate in spaced relation with one of said strip-inverting edges to provide therebetween a guide channel for the under-folded margin of the binding strip, and a strip-margin engaging member carried by said shell at a point remote from the fold-inverting end of the core-member, said strip-margin engaging member being formed and disposed with respect to said rib to provide therebetween a straight strip-guiding channel which communicates with said U-shaped channel and which terminates adjacent the juncture of said rib and said margin folding plate.

5. A strip-reversing binder for sewing machines, comprising, a core-member widthwise formed to provide a U-shaped outer guide-wall having substantially parallel outer side faces and lengthwise terminating in a notched strip-delivery mouth providing spaced strip-inverting edges inclined to the longitudinal axis of the core-member, a rib projecting substantially at right angles from one of said side faces and extending longitudinally of said core-member, an outer shell-member formed and disposed with respect to said core-member to provide therebetween a U-shaped strip-folding channel, said shell-member having a fold-defining side edge thereof disposed adjacent the juncture of said rib and said core-member side face at the fold-inverting end of the core, a strip-margin folding plate carried by and disposed substantially at right angles to said rib and overhanging said fold-defining edge of the shell-member, said plate having a free edge thereof inclined away from said rib and toward the delivery end of the binder to overhang said shell-member, a strip-confining guide-wall depending from said strip-margin folding plate in spaced relation with one of said strip-inverting edges to provide therebetween a guide channel for the underfolded margin of the binding strip, and a strip-margin engaging member carried by said shell at a point remote from the delivery end of the binder, said strip-margin engaging member being formed and disposed with respect to said rib to provide therebetween a straight strip-guiding channel which communicates with said U-shaped channel and which terminates adjacent the juncture of said rib and the inclined free edge of said strip-margin folding plate.

6. A strip-reversing binder for sewing machines, comprising, a core-member having a U-shaped outer guide-wall and having a notched strip-delivery mouth providing spaced strip-inverting edges inclined to the longitudinal axis of the core-member, said core-member having substantially parallel side faces each provided at the side edge thereof remote from the bend of said guide-wall with a rib extending longitudinally of the core-member, a first one of said ribs forming

a binding-strip edge-guide and the second one of said ribs projecting substantially at right angles from one of said side faces, a U-shaped shell-member disposed with respect to said core-member to form therewith a U-shaped strip-doubling channel, said shell-member having one limb disposed in strip-confining relation with said first rib and having its other limb terminating in a fold-defining side edge disposed adjacent the juncture of said second rib and said core side face, a strip-margin engaging member carried by said shell and formed and disposed with respect to said second rib to provide therebetween a straight strip-guiding channel which communicates with said U-shaped channel, a strip-margin folding plate carried by and disposed substantially at right angles to said second rib and overhanging said fold-defining edge of the shell-member at a point between the delivery end of the core-member and said strip-margin engaging member, said plate having a free edge thereof inclined away from said second rib and toward the delivery end of the binder to overhang said shell-member, and a strip-confining guide-wall depending from said strip-margin folding plate in spaced relation with one of said strip-inverting edges to provide therebetween a guide channel for the underfolded portion of the binding strip.

7. A strip-reversing binder for sewing machines, comprising, a core-member having a U-shaped wall terminating endwise of the binder in a notched strip-delivery mouth providing spaced strip-inverting edges inclined to the longitudinal axis of said core-member, said wall terminating widthwise of the binder in oppositely directed guide-ribs substantially normal to the wall and extending longitudinally of the core-member, a U-shaped shell-member disposed with respect to said core-member to form therewith a U-shaped strip-doubling channel, a plate extending from one of said ribs and overhanging an edge portion of said shell-member in proximity to the strip-delivery end of the binder, said plate having a strip-margin folding edge inclined to the length of the binder and terminating in an edge-guiding flange depending from said plate into contact with said shell-member, and said flange being bent about one of the strip-inverting edges of said core-member in spaced relation thereto.
